LEAD PENCIL

Clarence F. Norlin, Chicago, Ill.

Refiled for abandoned application Serial No.
738,617, September 19, 1924. This application
April 8, 1933. Serial No. 665,147

20 Claims. (Cl. 120—18)

My invention relates, more particularly, to lead pencils, of the so called magazine type, wherein leads to be successively used in the pencil, are stored.

5 My primary objects are to provide a novel, simple and economical construction of lead pencil of the type above referred to; to provide a construction whereby the leads may be quickly operatively positioned, in succession, for use in 10 the pencil; and other objects as will be manifest from the following description.

Referring to the accompanying drawings:—

Figure 1 is a view in longitudinal sectional elevation of a pencil embodying my improvements, the lead-feeding means being shown in the extreme position occupied by them in the feeding position. Figure 2 is a view in elevation, with certain parts broken away, of a portion of the lead feeding-means. Figure 3 is a view like Fig. 16 20 ure 1, with certain parts broken away of the structure therein illustrated, showing the lead-feeding means in an intermediate position occupied thereby in the operation of recharging the tip of the pencil with a lead. Figure 4 is a view like Fig. 3 showing the lead-feeding means in the extreme position occupied by them in the operation of charging a lead into said tip. Figure 5 is a view in side elevation of a detail of the pen- 25 cil. Figure 6 is a similar view of the opposite end of the pencil. Figure 7 is a section taken at the line 7 on Fig. 4 and viewed in the direction of the arrow. Figure 8 is a cross-sectional view taken through the compartment of the body of the pencil in which the lead magazine is located, 30 the said magazine and the spring-equipped cover therefor, being omitted; and Figure 9, a sectional view through the magazine showing three leads 35 therein as represented in Fig. 4.

The body of the pencil and represented at 10, 40 is in the form of a shell 11 open at one end and provided at its opposite end with a tip portion 12 containing a bore 13 extending longitudinally and centrally therethrough, the tip 12 being of tapered form as is common in magazine lead 45 pencils. The space provided within the shell 11 is divided to form two compartments 14 and 15, by a partition-desk 16 rigidly held in place in the shell at an annular shoulder 17 therein, the disk 16 being provided with an aperture 18 which 50 is in alignment with the bore 13 of the tip. The magazine in which the leads are stored for successive use, is represented generally at 19 and in the particular construction shown is in the form relatively, of a long and narrow box-like struc- 55 ture comprising the side-walls 20, end walls 21

and bottom wall 22. The width of the storage space provided in the magazine 19 and represented at 23 is slightly greater than the diameter of the leads to be used in the pencil and represented at 24, so that leads introduced into the magazine, are arranged in a single series, but as will be understood it is not necessary, so far as certain features of my invention are concerned, to provide a magazine of such form that the leads will be held in a single series as stated. 60 The end walls 21 of the magazine are apertured, as represented at 25, in alignment with the bore 13 and the aperture 18 in the disk 16, the apertures 25 extending flush with the inner surface of the bottom-wall 22 of the magazine, as shown, 70 whereby a lead lying against this bottom wall will be in alignment with the bore 13 and the aperture 18. The magazine referred to is shown as held in position by fitting into recesses 26 and 27 formed in the opposing faces of the disk 16 and 75 the end-wall at the opposite end of the compartment 14, as represented, the side walls of the magazine 19 being shown as extending short of the circumference of the body 10, means are preferably provided for constantly urging the 80 leads 24 toward the bottom-wall 22 of the magazine, these means, in the particular construction shown, comprising a spring-device 28 carried by a bar 29 located at an opening 30 in the shell 11 adjacent the open side of the magazine 19 and 85 serving as a removable closure therefor. The bar 29 is pivoted, as represented at 31, to the partition-disk 16, to adapt it to be swung toward and away from the magazine 19, its outer end being provided with an inwardly-extending lip 90 32 which, in the closed condition of the cover, bears with sufficient friction against the wall of recess 26 to hold the cover against accidental displacement. The spring device 28 shown comprises a leaf-spring section 33 rigidly secured at 95 one end to the cover bar 29 and rigidly secured at its deflected free end with a reversely-bent leaf-spring section 34, the connection of the section 33 with the section 34, being between the ends of the latter. The arrangement just described is such that the deflected portions of the leaf-spring 34 bear against the side of the adjacent one of the leads 24 and serve to force all of the leads in a direction toward the bottom wall 22 of the magazine. 100

The means for feeding the leads in succession into the tip of the pencil, comprise a feed-rod 35 disposed concentrically with the shell 11 and adapted to be moved through the aperture 18 in the disk 16, the openings in the end-walls of 110

the magazine and the bore 13. The rear end of the feed-rod 35 presents an enlarged cylindrical section 36 rigid with the forward, reduced, end thereof, the periphery of the section 36 containing a spiral groove 37. The portion 36 of the feed-rod 35 has sliding fit in the opening 38 in the end-wall 39 of a tube 40, the outer end of which latter is provided with a head 41 through the medium of which this tube, together with the feed-rod, is adapted to be rotated, the section 36 of the rod carrying a crosswise-extending pin 42 which extends at its opposite ends into, and is slideable in, diametrically opposed slots 43 located in the side-wall of the tube 40 and extending lengthwise of the latter. It may be here stated that a coil-spring 44 surrounds the portion 36 of the feed-rod and is confined between the end-wall 39 of the tube 40 and the pin 42, this spring tending to move the feed-rod to the left in the tube 40 to the position shown in Fig. 4. Surrounding the tube 40 is another tube 45 in which the tube 40 is rotatable, these two tubes being held against relative lengthwise movement as for example by means of the head 46 of tube 45 which extends into an angular groove 40A in the periphery of the tube 40. The tube 45 is provided with a pin 47 slideable crosswise of this tube in an opening 48 therein, into and out of a position in which it extends into the spiral groove 37 in the feed-rod, the outer end of this pin being carried by the free end of a leaf-spring 49 secured at its front end, as represented at 50, to the outer surface of the forward end of the tube 45 and extending lengthwise of the latter. The spring 49 functions to yieldably hold the pin 47 in the groove 37, to effect lengthwise movement of the feed-rod when the latter is rotated, by rotating the head 41. In the particular construction shown, it is desired that, in the operation of charging a new lead into the tip of the pencil, the pin 47 be withdrawn, preferably automatically, from the groove 37, and to accomplish this I provide, on a ring 51 rigidly mounted in the rear end portion of the shell 11, and through which the tube 45 slides, an annular 45 forwardly-inclined surface 52 which extends into the path of movement of the rear end 49A of the spring 49, which projects rearwardly beyond the pin 47 and serves, when the parts of the structure are moved to the position in Fig. 4, to cam the spring 49 and the pin 47 thereon, to the position shown in this figure in which the pin is withdrawn from the spiral groove 37.

Provision is also preferably made for releasably locking the head 46 to the shell 11, these means, in the arrangement shown, involving the grooving, as indicated at 53, of the forward face of the head 46 to receive the rear end of shell 11, and the provision in the head 46 of diametrically-opposed pins 54 which extend crosswise through these grooves and are adapted to enter bayonet, slots 55 in the wall of shell 11, when the parts are assembled to the position shown in Fig. 1.

The manner of manipulating the pencil is as follows. Assuming that the magazine is charged with leads as shown in Fig. 1, and that the feed-rod 35 extends to the limit of its lead-feeding movement to the right in Fig. 1, the operator, to recharge the bore 13 of the tip with another lead, first rotates the head 46, and with it the tube 45 carried thereby, while holding the shell 11 against rotation, to a position in which the pins 54 register with the portions of the bayonet-slots 55 which extend lengthwise of the pencil, and thereupon slides this head, and with it the tube 45 and the parts carried thereby and also the tube

40 and the feed rod 35, the engagement of the sliding pin 47 with the spiral groove 37 being undisturbed, to the position shown in Fig. 3, in which position the feed-rod 35 is moved to a position in which its forward extremity extends substantially flush with the rear end-wall of the tip of the pencil. Further movements of the parts just described to the left in Fig. 3, causes the portion 49A of the leaf spring 49, to engage, and ride upon, the inclined surface 52, whereupon the pin 47 is withdrawn from the spiral groove 37, thus relieving the restraint on the coil spring 44, (the latter being in compressed condition during the operation stated), whereupon this spring rapidly shifts the feed-rod 35 to the left in Fig. 3 to the position shown in Fig. 4 in which position the forward end of the feed-rod is withdrawn to a position in which it extends wholly exteriorly of the lead magazine. With the feed-rod thus withdrawn from the magazine, the spring 28 shifts all of the leads toward the bottom wall 22 of the magazine, thereby positioning the innermost lead in line with the bore 13 in the tip and the feed-rod 35. The operator then pushes forwardly on the head 46 with the result of moving the tubes 40 and 45, as a unit to the right in Fig. 4 to the position shown in Fig. 1, whereupon the operator rotates the head referred to, to a position in which it interlocks with the shell at the bayonet-slots therein. In the operation of pushing the head 46 forwardly as stated, the leaf-spring 49 disengages from the cam surfaces 52 and the pin 47 again enters the spiral groove 37, but as the spring 44 is in the extended position referred to, this pin enters the forward end of the spiral groove 37. In thus manipulating the parts, the feed-rod 35 moves forwardly and pushes the innermost lead out of the magazine, through the openings in the end walls, into the bore 13 in the tip 12, to position it to be fed therefrom into the position for use, by rotating the head 41, the rotation of which causes the tube 40, together with the feed-rod 35, to rotate in the tube 45 which rotation, due to the fact that the pin 47 extends into the spiral groove 37, causes the feed-rod 35 to move forwardly to feed the lead out through the tip, the spring 44 becoming compressed in this operation.

It will be understood from the foregoing description that a pencil constructed in accordance with my invention, while providing positive means for feeding a lead, as desired, into position for use, as the lead wears away, permits of ready recharging of the tip of the pencil with a new lead by an operation which may be quickly performed.

While I have illustrated and described a particular construction embodying my invention, I do not wish to be understood as intending to limit it thereto as the same may be variously modified and altered without departing from the spirit of my invention.

What I claim as new, and desire to secure by Letters Patent, is:

1. In a magazine pencil, the combination of a member containing a passage in which the leads, when positioned for use, extend, said member containing a recess one portion of which is continuous with said passage and which extends laterally through the side of the pencil to form a magazine, a cover for said recess, spring means carried by said cover and yieldingly pressing leads in the magazine into substantial alinement with said passage and means for feeding the

- leads in succession, from said magazine into said passage.

2. In a lead pencil, the combination of a member containing a passage in which the lead, when positioned for use, extends, the structure presenting a space to receive a lead in substantial alinement with said passage, and lead-feeding means comprising an element movable lengthwise of the pencil and adapted to engage the lead to feed it into said passage, yieldable means operating to move said element in a direction away from said passage, and in the lead-feeding movement of said element becoming tensioned, and releasable means for retaining said element against movement, under the action of said yieldable means, in the forwardly projected position of said element.

3. In a lead pencil, the combination of a member containing a passage in which the lead, when positioned for use, extends, the structure presenting a space to receive a lead in substantial alinement with said passage, and lead-feeding means comprising an element mounted to rotate and move lengthwise of the pencil and an element stationarily mounted relative to said first-named element, said elements having inter-engaging portions which operate to cause said first-named element to move lengthwise in the lead feeding direction when rotated, said elements being relatively movable into and out of engagement at said portions, and yieldable means in opposition to which said first-named element moves in the lead-feeding movement thereof.

4. In a lead pencil, the combination of a member containing a passage in which the lead, when positioned for use, extends, the structure presenting a space to receive a lead in substantial alinement with said passage, and lead-feeding means comprising an element mounted to rotate and move lengthwise of the pencil and having a spiral groove on its periphery, a pin stationarily mounted relative to said element and adapted to be moved into and out of said groove, and yieldable means in opposition to which said element moves lengthwise in the lead-feeding movement of said element.

5. In a lead pencil, the combination of a member containing a passage in which the lead, when positioned for use, extends, the structure presenting a space to receive a lead in substantial alinement with said passage, and lead-feeding means comprising elements movable together in a direction lengthwise of the pencil, one of said elements being movable relative to the other thereof in a direction lengthwise thereof, yieldable means operating to move one of said elements in a direction away from said passage and in the movement thereof to forwardly projected position becoming tensioned, and releasable means for restraining said last-referred-to element against movement under the action of said yieldable means, in its forwardly projected position.

6. In a lead pencil, the combination of a member containing a passage in which the lead, when positioned for use, extends, the structure presenting a space to receive a lead in substantial alinement with said passage, and lead-feeding means comprising elements movable together in a direction lengthwise of the pencil, one of said elements being adapted to rotate and move lengthwise of the other of said elements, a third element stationarily mounted relative to said rotatable element, said rotatable element and said third element having inter-engaging portions which operate to cause said rotatable element to move lengthwise, in the lead-feeding direction, when rotated, said interengaging portions being relatively movable into and out of engagement, yieldable means operating to move said rotatable element in a direction away from said passage and the movement thereof to forwardly projected position becoming tensioned, and means operating automatically to disengage said portions in the movement of said first-referred-to elements lengthwise of the pencil to a predetermined position.

7. In a lead pencil, the combination of a member containing a passage in which the lead, when positioned for use, extends, the structure presenting a space to receive a lead in substantial alinement with said passage, and lead-feeding means comprising elements movable together in a direction lengthwise of the pencil, one of said elements being mounted to rotate and move lengthwise relative to the other thereof and having a spiral groove in its periphery, a pin stationarily mounted relative to said rotatable element and adapted to be moved into and out of said groove, and yieldable means operating to move said rotatable element in a direction away from said passage and in the movement thereof to forwardly projected position becoming tensioned.

8. In a lead pencil, the combination of a member containing a passage in which the lead, when positioned for use, extends, the structure presenting a space to receive a lead in substantial alinement with said passage, and lead-feeding means comprising elements movable together in a direction lengthwise of the pencil, one of said elements being movable relative to the other thereof in a direction lengthwise thereof, yieldable means operating to move one of said elements in a direction away from said passage and in the movement thereof to forwardly projected position becoming tensioned, releasable means for restraining said last-referred-to element against movement under the action of said yieldable means, in its forwardly projected position, and means operating automatically to release said releasable means in the relative movement of said elements to a predetermined position.

9. In a lead pencil, the combination of a member containing a passage in which the lead, when positioned for use extends, the structure presenting a space to receive a lead in substantial alinement with said passage, and lead-feeding means comprising elements movable together in a direction lengthwise of the pencil, one of said elements being adapted to rotate and move lengthwise of the other of said elements, a third element stationarily mounted relative to said rotatable element, said rotatable element and said third element having inter-engaging portions which operate to cause said rotatable element to move lengthwise, in the lead-feeding direction, when rotated, said interengaging portions being relatively movable into and out of engagement, yieldable means operating to move said rotatable element in a direction away from said passage and the movement thereof to forwardly projected position becoming tensioned, and means operating automatically to disengage said portions in the movement of said first-referred-to elements lengthwise of the pencil to a predetermined position.

10. In a lead pencil, the combination of a member containing a passage in which the lead, when positioned for use, extends, the structure presenting a space to receive a lead in substantial alinement with said passage, and lead-feeding means comprising elements movable together in a direction lengthwise of the pencil, one of said elements being mounted to rotate and move lengthwise relative to the other thereof and having a spiral groove in its periphery, a pin stationarily mounted relative to said rotatable element and adapted to be moved into and out of said groove, and yieldable means operating to move said rotatable element in a direction away from said passage and in the movement thereof to forwardly projected position becoming tensioned.

- tion lengthwise of the pencil, one of said elements being mounted to rotate and move lengthwise relative to the other thereof and having a spiral groove in its periphery, a pin stationarily mounted relative to said rotatable element and adapted to be moved into and out of said groove, yieldable means operating to move said rotatable element in a direction away from said passage and in the movement thereof to forwardly projected position becoming tensioned, and means operating automatically to move said pin out of engagement with said groove in the movement of said elements lengthwise of the pencil to a predetermined position.
15. 11. In a lead pencil, the combination of a member containing a passage in which the lead, when positioned for use, extends, the structure presenting a space to receive a lead in substantial alignment with said passage, and lead-feeding means comprising telescope members, the inner one of which is rotatable relative to the outer one of said members, a lead-feeding rod for moving the lead in said passage, a pin and slot connection between said rod and the rotatable one of said members, whereby said rod is adapted to be rotated by rotation of said rotatable member and is permitted to move lengthwise of the latter, a spring tending to hold said rod in retracted position, and means on said rod and the other one of said members for causing said rod to be advanced, against the action of said spring, when said rotatable member is rotated, said means comprising a part which is carried by the other of said members and operatively engages said rod and is releasable to permit said spring, to move said rod on said rotatable member, in a direction to retract said rod.
12. In a lead pencil, the combination of a member containing a passage in which the lead, when positioned for use, extends, the structure presenting a space to receive a lead in substantial alignment with said passage, and lead-feeding means comprising telescoped members, the inner one of which is rotatable relative to the outer one of said members, a lead-feeding rod for moving the lead in said passage, a pin and slot connection between said rod and the rotatable one of said members, whereby said rod is adapted to be rotated by rotation of said rotatable member and is permitted to move lengthwise of the latter, a spring tending to hold said rod in retracted position, said rod containing a spiral groove in its periphery, and a pin carried by the other one of said members and movable into and out of a position in which it extends into said groove.
13. In a lead pencil, the combination of a member containing a passage in which the lead, when positioned for use, extends, the structure presenting a space to receive a lead in substantial alignment with said passage, and lead-feeding means comprising telescoped members, the inner one of which is rotatable relative to the outer one of said members, a lead-feeding rod for moving the lead in said passage, a pin and slot connection between said rod and the rotatable one of said members, whereby said rod is adapted to be rotated by rotation of said rotatable member and is permitted to move lengthwise of the latter, a spring tending to hold said rod in retracted position, said rod containing a spiral groove in its periphery, a pin carried by the outer one of said members and movable into and out of a position in which it extends into said groove, and means, operating automatically upon the movement of said members together toward retracted position, to disengage said pin from said groove.
14. In a lead pencil, the combination of a member containing a passage in which the lead, when positioned for use, extends, the structure presenting a space to receive a lead in substantial alignment with said passage, and lead-feeding means comprising telescoping tubes, the inner one of which is rotatable in the other of said tubes, said inner tube containing a guide slot extending lengthwise thereof, a lead-forcing rod slidably mounted to move lengthwise in the inner one of said tubes, a pin on said rod extending into said guide slot, a spring operatively engaging said rod and tending to move the latter to retracted position, said rod containing a spiral groove in its periphery, the outer one of said tubes containing an opening in its side wall, a spring device carried by said outer tube and having a part which extends through said opening and into said spiral groove, and a member stationarily supported relative to said tubes and adapted to be engaged by said spring device, to withdraw said projection from said groove, upon the movement of said tubes to retracted position.
15. In a lead pencil, the combination of a member containing a passage in which the lead, when positioned for use, extends, the structure presenting a space to receive a lead in substantial alignment with said passage, and lead-feeding means comprising an element movable lengthwise of the pencil, a second element movable lengthwise of the pencil and adapted for lengthwise movement relative to said first-named element and adapted to be rotated, a third element stationarily mounted relative to said second element, said element and said third element having interengaging portions which operate to cause said second element to move lengthwise, in the lead-feeding direction, when rotated, said interengaging portions being relatively movable into and out of engagement, and yieldable means engaging said first-named element and said second element and operating to move said second element in a direction away from said passage and in movement thereof to forwardly projected position becoming tensioned.
16. In a lead pencil, the combination of a member containing a passage in which the lead, when positioned, for use, extends, the structure presenting a space to receive a lead in substantial alignment with said passage, and lead-feeding means comprising an element movable lengthwise of the pencil, a second element movable lengthwise of the pencil and adapted for lengthwise movement relative to said first-named element and adapted to be rotated, said second element having a spiral groove in its periphery, a pin stationarily mounted relative to said second element and adapted to be moved into and out of said groove, and yieldable means engaging said first-named and said second element and operating to move said second element in a direction away from said passage and in the movement thereof to forwardly projected position becoming tensioned.
17. In a lead pencil, the combination of a member containing a passage in which the lead, when positioned for use, extends, the structure presenting a space to receive a lead in substantial alignment with said passage, and lead-feeding means comprising an element movable lengthwise of the pencil, a second element movable lengthwise of the pencil and adapted for lengthwise movement relative to said first-named element and adapted to be rotated, a third element

element stationarily mounted relative to said second element, said second element and said third element having interengaging portions which operate to cause said second element to move lengthwise, in the lead-feeding direction, when rotated, said interengaging portions being relatively movable into and out of engagement, yieldable means engaging said first named element and said second element and operating to move said second element in a direction away from said passage and in the movement thereof to forwardly projected position becoming tensioned, and means operating automatically to disengage said portions in the movement of said first-named element and said second element to a predetermined position.

18. In a lead pencil, the combination of a member containing a passage in which the lead, when positioned for use, extends, the structure presenting a space to receive a lead in substantial alinement with said passage, and lead-feeding means comprising an element movable together lengthwise of the pencil, a second element movable lengthwise of the pencil and adapted for lengthwise movement relative to said first named element and adapted to be rotated, said second element having a spiral groove in its periphery, a pin stationarily mounted relative to said second element and adapted to be moved into and out of said groove, yieldable means engaging said first-named element and said second element and operating to move said second element in a direction away from said passage and in the movement thereof to forwardly projected position becoming tensioned, and means operating automatically to move said pin out of engagement with said groove in the relative movement of said first-named element and said second element to a predetermined position.

40 19. In a lead pencil, the combination of a member containing a passage in which the lead, when positioned for use, extends, the structure presenting a space to receive a lead in substantial alinement with said passage, and lead-feeding

means comprising members operatively engaged to move together lengthwise of the pencil, one of said members being rotatable relative to the other thereof, a lead-feeding rod for moving the lead in said passage, a pin and slot connection between said rod and the rotatable one of said members, whereby said rod is adapted to be rotated by rotation of said rotatable member and is permitted to move lengthwise of the latter, a spring tending to hold said rod in retracted position, and means on said rod and the other one of said members for causing said rod to be advanced, against the action of said spring, when said rotatable member is rotated, said means comprising a part which is carried by the other of said members and operatively engages said rod and is releasable to permit said spring, to move said rod on said rotatable member, in a direction to retract said rod.

20. In a lead pencil, the combination of a member containing a passage in which the lead, when positioned for use, extends, the structure presenting a space to receive a lead in substantial alinement with said passage, and lead-feeding means comprising a rotatable element movable lengthwise of the pencil, a second, rotatable, element movable lengthwise of the pencil and adapted for lengthwise movement relative to said first-named element, means whereby said second element is rotated by said first-named element, a third element stationarily mounted relative to said rotatable element, said rotatable element and said third element having interengaging portions which operate to cause said rotatable element to move lengthwise, in the lead-feeding direction, when rotated, said interengaging portions being relatively movable into and out of engagement, and yieldable means operating to move said rotatable element in a direction away from said passage and in the movement thereof to forwardly projected position becoming tensioned.
